4 Claims. (Cl. 123—176)

The present invention relates to machines provided with means for the evacuation of calories from some of their elements. It is more especially, although not exclusively concerned with internal combustion engines, and more particularly those of the fuel injection type.

The object of the present invention is to provide machines of this type which are better adapted to meet the requirements of actual practice.

According to the present invention, the elements of these machines that are intended to serve to the evacuation of heat consist of the combination of at least two parts juxtaposed together and one of which is to give off heat to the other one. The essential feature of the present invention consists in so devising these parts that at least portions of their faces constitute walls of a closed chamber which is filled with a compressed metallic powder.

Preferably, this metallic powder must be a powder of a metal which is a good conductor of heat, for instance aluminium.

These, and other, features of the present invention will clearly result from the following detailed description of some specific embodiments of said invention.

Preferred embodiments of the present invention will be hereinafter described, with reference to the accompanying drawing, given merely by way of example, and in which:

Fig. 1 is an axial vertical sectional view of the upper part of a cylinder and the corresponding piston of a fuel injection internal combustion engine made according to the invention;

Fig. 2 is an axial vertical sectional view of the cylinder head of an explosion engine of the valve type showing another manner of employing the present invention.

The embodiments of the present invention that will be hereinafter described illustrate the application of the invention to an internal combustion engine.

In an internal combustion engine according to the present invention, all the parts, with the exception of those that must serve to the evacuation of calories, may be made of any suitable conventional or other structure. The parts serving to the evacuation of heat consist of the assembly of at least two elements juxtaposed to each other and one of which must give off calories to the other one. For instance, at least some portions of the combustion chamber of the engine constitute one of these two elements.

According to the present invention, the heat given off by the combustion of fuel in an internal combustion engine is evacuated through at least two parts from one of which the calories flow to the other, said parts being so devised that at least portions of their faces constitute walls of a closed

chamber, which chamber is filled with compressed metallic powder. Advantageously, certain portions of the walls of said chamber are so devised as to ensure the removal of the calories transmitted through said metallic powder.

Of course, according to the invention, any metallic powder may be used, but, advantageously, use should be made of a powder of a metal which is a good conductor of heat, such for instance as aluminium.

Furthermore, this metal is particularly advantageous in the case of the invention being applied to the pistons of internal combustion engines, because it is advantageous to obtain pistons that are as light as possible.

An internal combustion engine piston according to the invention is shown by way of example in Fig. 1. In this embodiment of the invention, the cushion of metallic powder above mentioned is shown at *a*. A sufficient amount of said metallic powder is poured into the inside of the piston, previously placed upside down, in order to obtain a cushion *a* of metallic powder compressed and maintained by a partition *b* of suitable shape. Advantageously, this partition *b* is positioned below the zone of the piston skirt carrying the upper packing rings. Partition *b* may be provided, on its outer face, that is to say on its face that is not in contact with the cushion *a* of metallic powder, with cooling ribs or projections *c*.

When the internal combustion engine piston is of the type including, in its central portion, a projection *d* on which is directed and impinges the jet from the injector, said projection is advantageously carried by a part *e*, for instance of special steel, which is screwed, or fixed in position in any other way, on the body *f* of the piston, which is, for instance, made of cast iron. Advantageously, this part *e* is so hollowed out that the metallic powder may have therewith a surface of contact as large as possible. Furthermore the walls of said part *e* can be given a reduced thickness, which is very advantageous because the thermic conductibility of the material (for instance special steel) of which part *e* is made is lower than that of the compressed metallic powder that constitutes cushion *a*.

Fig. 1 also shows the application of the invention to the cylinder head of an internal combustion engine of the type including a tore-shaped combustion chamber *g*.

According to this embodiment, the outer walls of said combustion chamber are surrounded by a chamber closed, on the outside by a wall *h* which is for instance in contact with the cooling water of the engine, or with any suitable cooling fluid.

The chamber thus surrounding the combustion

chamber of the engine is filled with compressed metallic powder.

Fig. 2 shows the application of the invention to internal combustion engines provided with 5 two valves disposed side by side.

According to this embodiment, instead of providing, in the space located between the pipes leading to the seats of these valves, a thin sheet of water, according to the usual practice (which 10 has the drawback of producing a rapid scaling of this space), a cushion *i* of metallic powder is provided in said space. The chamber in which this cushion is enclosed is formed by a portion of the cylinder head and a wall or partition *j* advantageously provided with cooling ribs or projections. These ribs or projections contact with the engine cooling water, which is contained in jacket *k*.

It will be readily understood that, whatever 20 be the specific embodiment, the cushion of metallic powder is perfectly in contact with the surfaces of the parts between which a flow of calories is to take place, so that this passage of the calories from one part to the other will take place 25 under much better conditions than if a solid metallic mass had been applied against said surfaces.

As a matter of fact, for practical purposes, 30 it is impossible to obtain that two metallic surfaces are in contact with each other over their whole area.

Two metallic surfaces can contact each other only at certain points, the number of which may be very great but does not ensure a passage of the calories from one surface to the other as good as if a perfect contact could be obtained.

Now this perfect contact is obtained in a 35 wholly satisfactory manner through the metallic powder, and even if it so happens that the thermic conductibility of said powder is lower than that of the metal of which it is made, yet the passage of the calories takes place under much better conditions than if a solid metallic mass were used.

Another advantage of the use of compressed 45 metallic powder as filling material over the use of a block of solid material is obtained when said filling material must consist of a metal that is very much dilatable, such as aluminium. This 50 is due to the fact that a powder, due to its elasticity, cannot have any injurious action in spite of its high coefficient of expansion, even when it is enclosed in a chamber made of a material having a coefficient of expansion lower than that of the matter of which the filling cushion is made.

This advantage is particularly great when the 60 parts of the engine, such for instance as a piston or a cylinder head consists of the juxtaposition of elements made of different metals, and therefore having different coefficients of expansion. In this case also, the thermic connection between these elements is obtained in a much 65 more satisfactory manner with metallic powder than with a block of light metal such as those utilized up to the present time for this purpose.

Furthermore, a compressed metallic powder 70 prevents the unscrewing of the various nuts, (such for instance as those serving to fix in position projection *d*, above mentioned with reference to Fig. 1) through which the elements are assembled together and it forms a packing element between them.

It should be noted that, in the case of pistons the last mentioned advantage is very precious for

preventing not only leakage of gases from the combustion chamber, but also, and chiefly, leakage of air and oil from the inside of the piston. As a matter of fact, the last mentioned leakage would permit oil to penetrate into the piston, where it would be calcined, which would subsequently produce dilatations causing seizing or breaking. 5

Finally, in the case of pistons provided with a projection *d* of the kind of that shown in Fig. 10 1, the presence, under the piston head, of a cushion of compressed metallic powder reinforces the piston head and makes it possible to make it of a relatively small thickness, in spite of the high temperature to which it is subjected during working 15 and of the relatively bad mechanical properties of the metals of which piston heads are generally made.

While there are in the preceding description, 20 disclosed what are deemed to be practical and efficient embodiments of the present invention, it should be well understood that it is not desired to be limited thereto as there might be changes made in the arrangement, disposition and form of the parts without departing from 25 the principle of the present invention as comprehended within the scope of the appended claims.

What is claimed is:

1. In a machine, the combination of at least 30 two parts made of materials having different respective coefficients of expansion, one of which parts is intended to give off heat to the other one, when in operation, at least portions of the faces of said parts constituting walls of a closed 35 chamber, and a metallic powder filling up said chamber compressed therein.

2. In a machine part the combination of at 40 least two parts made of materials having different respective coefficients of expansion and contacting one another, portions of the faces of said parts adjacent the joints between them constituting at least a portion of the walls of a closed chamber, and a metallic powder filling up said chamber and compressed therein to conduct 45 heat off from said parts and to tighten the joints between them.

3. A piston comprising in combination at least 50 two parts made of materials having different respective coefficients of expansion and contacting one another, portions of the faces of said parts adjacent the joints between them constituting at least a portion of the walls of a closed chamber, and a metallic powder filling up said chamber and compressed therein to conduct heat off 55 from said parts and to tighten the joints between them.

4. A piston for internal combustion engines, 60 which comprises in combination a piston end, a hollow projection fixed to the central part of said piston end and extending on the outer side thereof, said piston end and said projection being made of materials having different respective coefficients of expansion, a piston skirt, a partition carried by said piston skirt, so as to form 65 inside said piston a closed chamber limited by said piston end, the inside of said hollow projection, said piston skirt and said partition, and a metallic powder filling up said chamber and compressed therein. 70
